LOOSE-LEAF BINDER

Edward F. Buenger, River Forest, and Fred D. Wedge, Oak Park, Ill., assignors to Wilson-Jones Company, Chicago, Ill., a corporation of Massachusetts

Application November 15, 1949, Serial No. 127,412

1 Claim. (Cl. 129—8)

1 This invention relates to a loose leaf binder, and particularly to a post binder having a reference position in which the binder back is expanded to provide visual access to the contents without permitting removal of the sheets.

The loose leaf binder with which the present invention is concerned is specifically designed to hold catalog sheets, or similar sheets to which reference must be made frequently, and sheet changes are relatively few. When the sheets are not being referred to it is necessary to have them compressed so that the binder may be stored without taking up too much space and may be handled without tearing the sheets. However, when the sheets are compressed it is difficult to spread them open to the extent necessary for easy reading.

The principal object of our invention is to provide a post binder adapted to hold the sheet contents securely in closed position, and may be readily expanded to an intermediate reference position while still holding the sheets against removal or may be opened easily to permit the addition or removal of sheets. Other objects will become apparent upon reading the following description, taken in conjunction with the accompanying drawings, in which:

Figure 1 is a perspective view of a binder embodying the invention, showing the top cover opened with the sheet contents locked in closed position;

Figure 2 is a fragmentary top plan view of the binder with the sheet retaining mechanism locked in closed position;

Figure 3 is a side elevation of the binder with the lock slide in locked position;

Figure 4 is a fragmentary plan view of the binder in intermediate position;

Figure 5 is a fragmentary side elevation showing the pivoted latch in open position;

Figure 6 is a fragmentary top plan view with the sheet retaining mechanism in open position;

Figure 7 is a side elevation of the binder with the lock slide in open position;

Figure 8 is a longitudinal sectional view taken along the line 8—8 of Figure 2; and

Figure 9 is a cross sectional view taken along the line 9—9 of Figure 6 and showing, in dotted lines, the sheet retaining posts partially raised with the transfer bar removed.

In the drawings, the reference numerals 2 and 3 indicate a pair of complementary back sections. Back section 3 has a supplemental metal plate 4 permanently secured to its top surface in any suitable manner. Each end of the plate 4 is pro-

2 vided with an inwardly extending channel 5 embracing the corresponding end of section 2 so that the back sections may be moved transversely relative to each other. The inner end 6 of the top wall of each channel 4 is wider than the rest of the top wall to form a shoulder 7. A lug 8 projects upwardly from back section 2 adjacent to its inner edge at each end thereof. The lugs 8 are preferably struck from the back section 2, but they may be formed separately and welded thereto. The lugs 8 engage the shoulders 7 when the back sections are moved outwardly and act as stop members to prevent separation of the back sections.

15 A cover member 9 and a flat plate 10 are hinged to the outer edge of back section 2, as indicated at 11. The plate 10 carries a pair of tubular sheet retaining posts 12, rigidly secured thereto. A cover member 13 is hinged to back section 3, as indicated at 14. The plate 4 is slightly narrower than back section 3 and has its outer edge bent upwardly to form a flange 15 positioned a short distance in front of the hinge 14.

20 A lock slide 16 is permanently secured to the outer surface of flange 15 by means of plurality of rivets or studs 17 which pass through elongated slots 18 in the lock slide. The length of slots 18 will of course determine the distance the lock slide is permitted to move relative to the flange 15. One end of the lock slide extends beyond the end of flange 15 and is bent inwardly to form a lip 16' to facilitate the longitudinal movement of the lock slide with sufficient friction to hold the slide in any position to which it is moved.

25 The lock slide 16 is provided with a pair of bayonet slots 19 open at one edge and having their restricted portions parallel to slots 18. The flange 15 is provided with apertures 20 adapted to register with the open ends of the bayonet slots when the lock slide is pulled outwardly to its open position. A transfer bar 21 having solid posts 22 telescoping into the tubular posts 12 is provided with studs 23 which cooperate with lock slide 16 to secure the transfer bar in the binder. The studs are rigidly secured to the transfer bar and have a reduced neck portion 24 adapted to fit in the restricted portion of the bayonet slots 19. When the studs 23 are engaged by the 30 restricted portions of bayonet slots 19 the back sections can be moved outwardly to the extent permitted by lugs 8 and shoulders 7, but in this position the posts 22 are still telescoped in tubular posts 12 and the transfer bar cannot be removed for the purpose of adding or removing

sheets. When the lock slide is pulled outwardly to its open position, the open portions of the bayonet slots are aligned with the studs, and the transfer bar may be easily removed.

A tubular post 25, similar to the posts 12, except that it is threaded on the inside, as indicated at 26, is secured to the plate 10 at the center of the plate in the same manner the posts 12 are secured. A stud 27 having a threaded shank 28 is threaded into post 25. The transfer bar 21 has an aperture 29 large enough to permit the head of the stud 27 to project therethrough. A collar 30 engages the transfer bar and prevents the stud from passing entirely through the aperture, 29. The flange 15 and lock slide 16 are provided with slots 31 and 32 respectively, each wide enough to permit the head of the stud 27 to pass therethrough. The slot 32 is elongated to permit sliding movement of lock slide 16.

A latch 33 is pivoted to the flange 15, as indicated at 34. The latch is offset slightly, as indicated at 35, so that it may swing over lock slide 16. The latch is provided with a notch 36 adapted to engage a reduced neck portion 37 on stud 27 to prevent relative movement of back sections 2 and 3. One edge of the latch has an upturned lip 38 to facilitate manipulation of the latch. The opposite edge of the latch is also provided with a turned up lip 39 adjacent to notch 36. The lock slide 16 is provided with a lug 40 which abuts lip 39 when the lock slide is in closed position and the notch 36 is in engagement with the reduced neck portion of stud 27. The lug 40 may be struck from the lock slide or may be formed separately and welded thereto.

When the sheets are impaled on posts 12 and 25 the transfer bar 21 is pressed against the sheets and the stud 27 is threaded into post 25 far enough so that the notch of latch 33 will engage the reduced neck portion of the stud 27. In this position, with the lock slide in closed position, the sheets are locked in the binder in compressed position. The latch 33 may be manually moved about its pivot to disengage the notch 36 from the stud, and the back sections 2 and 3 may be moved to intermediate reference position. However, in this position the studs 23 on the transfer bar are engaged by the restricted portions of the bayonet slots in the lock slide, and therefore, the transfer bar is locked in position and the sheets are held against removal.

If sheet changes are to be made, the lock slide may be pulled outwardly until the open edges of the bayonet slots are aligned with the studs 23. The transfer bar may then be moved at right angles to the flange 15 until studs 23 are clear

5 of the apertures 20 in the flange, and then moved pivotally with plate 10 about the hinge 11 until the transfer bar is clear of flange 15 so that it can be lifted to remove posts 22 from the tubular posts 12. Movement of the lock slide to open position when the notch 36 of latch 33 is engaged with the stud 27 causes the lug 40 to engage the lip 39 to automatically move the latch to open position so that it is possible to move the back sections from closed position to open position without first moving them to the intermediate position used for reference.

Although we have described a few embodiments of our invention in considerable detail, it will be understood that the drawings are intended to be illustrative, rather than restrictive, as many details may be modified or changed without departing from the spirit or scope of our invention. Accordingly, we do not desire to be restricted to the exact structures described except as limited by the appended claim.

We claim:

In a loose leaf binder, a pair of telescoping back sections, a post carrying plate hinged to one of said back sections, a plurality of sheet retaining posts rigidly secured to said plate, a flange rigidly secured to said other back section, a transfer bar positioned adjacent said flange, posts rigidly secured to said transfer bar and engaging said first mentioned posts in telescoping relationship, a lock slide mounted on said flange and operable to lock said transfer bar in position or to release it from locked position, another post rigidly secured to said hinged plate, said last mentioned post having a stud at its free end, said stud projecting through aligned apertures in said flange and said lock slide, a latch pivotally mounted on said flange, said latch engaging said stud to prevent relative movement of said back sections, and a lug projecting from said lock slide, said lug engaging said latch to move it out of engagement with said stud upon movement of said lock slide to open position.
